(57) **CLAIM**

I claim the ornamental design for a vehicle alignment and suspension adjuster, as shown and described.

DESCRIPTION

FIG. 1 is a perspective view of a vehicle alignment and suspension adjuster, showing my new design;

FIG. 2 is an exploded perspective view thereof;

FIG. 3 is a top plan view thereof, the bottom plan view being a mirror image thereof;

FIG. 4 is an exploded front elevational view thereof;

FIG. 5 is an exploded rear elevational view thereof;

FIG. 6 is an exploded left-side elevational view thereof; and,

FIG. 7 is an exploded right-side elevational view thereof.

The broken lines showing a vehicle suspension bracket in FIG. 1 depict environmental matter and form no part of the claimed design.
